US00D756371S

(12) **United States Design Patent**
Bertnick et al.

(10) **Patent No.:** **US D756,371 S**
(45) **Date of Patent:** **** May 17, 2016**

(54) **DISPLAY SCREEN WITH GRAPHICAL USER INTERFACE**

(71) Applicant: **Symantec Corporation**, Mountain View, CA (US)

(72) Inventors: **Joe Bertnick**, Houston, TX (US); **Shubhabrata Mohanty**, Maharashtra (IN); **Peggy J. Kirk**, Ben Lomond, CA (US)

(73) Assignee: **Symantec Corporation**, Mountain View, CA (US)

(**) Term: **14 Years**

(21) Appl. No.: **29/475,326**

(22) Filed: **Dec. 2, 2013**

(51) **LOC (10) Cl.** **14-04**

(52) **U.S. Cl.**

USPC **D14/485**

(58) **Field of Classification Search**

USPC D14/485-490

CPC G06F 3/0482; G06F 3/04842; G06F 3/04817

(57) **CLAIM**

The ornamental design for a display screen with graphical user interface, as shown and described.

DESCRIPTION

The FIGURE is a front view of a display screen with graphical user interface showing the claimed design.

The outer edge of the display screen is understood to be congruent with the outer edge of the graphical user interface.

1 Claim, 1 Drawing Sheet
